UNITED STATES PATENT OFFICE

ANDREW EKMAN, OF GRAND RAPIDS, MICHIGAN, ASSIGNOR TO WINTERS & CRAMPTON MANUFACTURING COMPANY, OF GRANDVILLE, MICHIGAN, A CORPORATION OF MICHIGAN

LOCKING REFRIGERATOR LATCH

Application filed May 19, 1930. Serial No. 453,554.

This invention relates to a latch structure particularly applicable for use on refrigerators and with which the refrigerator doors may be releasably held in closed position, combined with which is a simple, novel and effective key operated lock used to lock the latch bolt or lever of the latch mechanism against movement in its keeper so that the latch lever cannot be released to open the door. The present invention is directed to a very practical, simple and effective construction of the character outlined, having many novel features of construction and arrangements of parts for effectively attaining the ends desired, all of which will appear fully and in detail in the following description, taken in connection with the accompanying drawings, in which,

Fig. 1 is a fragmentary front elevation illustrating the latch mounted on a door and its keeper mounted on the door frame.

Fig. 2 is a vertical section substantially on the plane of line 2—2 of Fig. 1.

Fig. 3 is a side elevation of the keeper, the latch bolt being shown in transverse section.

Fig. 4 is an inner elevation of the latch construction with the base plate removed, showing the latch lever in its latching position.

Fig. 5 is a similar view with the latch lever in its unlatching position.

Figs. 6 and 7 are inner elevations of the base plate and the locking mechanism mounted thereon, the lock being shown in operative position in Fig. 6 and in the position to release the latch lever in Fig. 7.

Fig. 8 is a transverse section through the base plate and locking mechanism.

Fig. 9 is a perspective view of the latch mechanism and the base plate and lock thereon showing the parts separated, and

Fig. 10 is an elevation of a key used to operate the lock.

Like reference characters refer to like parts in the different figures of the drawings.

In the construction of the latch, which is to be mounted on the refrigerator door, a latch housing 1 of any conventional form may be provided having upwardly and downwardly extending attaching flanges 2. In the upper side of the housing an opening 3 is made

while one of the sides is cut away as indicated at 4 for the passage of the latching lever.

A post 5 extends downwardly from the upper side of the housing on which the latch lever 6 is pivotally mounted between its ends. The projecting free end of the lever may be equipped with a roller 7 in accordance with conventional practice. The lever is provided with a notch or recess 8 in one side adjacent its pivot and the inner end portion has an elongated opening therethrough. In the notch 8 of the lever and in a corner of the housing the heads of two sheet metal members 10 are received, the same extending toward each other. A coiled compression spring 11 is located around the shanks of said members 10, the shanks extending toward and overlapping each other, and the inner corner of the housing 1, as fully shown in Figs. 4 and 5.

At the opposite sides of the opening 3 in the outer side of the housing ears 12 extend outwardly through which a pivot pin 13 passes, serving to mount a depending or drop handle 14 which, at its upper end, is formed with an inwardly extending arm 15 passing through the opening 3 and into the elongated opening in the inner end portion of the latch lever 6. It is apparent that with this construction, on grasping the depending handle 14 and pulling outwardly thereon, the lever 6 may be turned from the position shown in Fig. 4 to that shown in Fig. 5. The line of force of the spring 11 is carried across the pivotal axis about which lever 6 moves so that the lever is yieldingly held in either of its positions, shown in Fig. 4 or Fig. 5, the force of the spring acting to hold the same in either position and the line of force of the spring crossing the pivotal axis about which the latch bolt turns.

The inner side of the housing is closed by a base plate 16 which fits in a suitable recess thereon made at the inner side of the housing and is secured in place by a screw 17 passing through the base and threading into the pivot post 5. A guide rib 18 is struck inwardly from the base 16, between which and a tongue 19 struck from the base, a lock bolt 20 is slidably mounted. The bolt 20 has a projecting

finger 21 at one side and is also provided with a notch 22 for the reception of the edge of an operating key to move the lock bolt 20 longitudinally. The bolt is held snugly against the base plate and frictionally held against accidental movement by a leaf spring 23 lying thereover which is held in place by a tongue 24 struck inwardly from the plate 16 and passing through a slot 25 in the bolt 20, and then through the spring 23, being riveted over at its outer end to cause the spring to bear with spring pressure upon the bolt 20.

A bracket 26 of the form shown is secured to the inner side of the base plate 16 and has a slot 27 in one side and a circular opening 15 through which the key barrel 28 passes, said barrel being rotatably mounted between the base plate 16 and the bracket 26 and extending to and through an opening in the top of the housing 1, whereby a key 29 (Fig. 10) 20 may be inserted lengthwise of the key barrel 28 when it is positioned so that its slot is in conjunction with the slot 27. The tongue 29a of the key is adapted to engage the latch bolt 20 in the notch 22 to move the bolt to its two 25 extremes of movement, one being that shown in Fig. 6 and the other in Fig. 7.

When the locking bolt 20 has been moved to the position shown in Fig. 6, it is evident 30 that the finger 21 lies in the path of movement of the inner end of the latch lever 6 so that the same can not be operated; but when the bolt has been moved to the position shown in Fig. 7, the finger 21 is beyond the inner end 9 35 of the latch lever and the lever may then be freely operated by the handle 14.

The latch structure is designed to be secured to a door 30 in the usual manner and the keeper used therewith to the door jamb 31. The keeper comprises a base 32 secured to the door jamb or frame, having an outwardly 40 extending post 33 which at its inner side is provided with a downwardly and inwardly curved recess 34 to receive the outer end of the latch lever. The keeper has a trip finger 35 45 at the upper side of the lever receiving recess while below said recess the keeper is formed with a downwardly and outwardly extending cam surface 36.

With the door in closed position, as shown 50 in Fig. 1, the latch lever is in its lower position corresponding to that illustrated in Fig. 6, in which position the locking bolt 20 may be operated so as to secure the latch bolt against movement. The refrigerator door accordingly may be securely locked against 55 opening. When the door is opened the latch lever has been moved from its lower position, shown in Figs. 1 and 4, to its upper position 60 such as shown in Figs. 5 and 7, clearing the keeper so that the door may be opened. On closing the door the raised upper outer end of the latch lever 6 strikes the finger 35 at the 65 under curved side thereof and automatically turns the lever to lower position whereby it

enters the keeper and holds the door tightly closed. Of course, if inadvertently or accidentally the latch bolt has been moved to its lower position before the door has been closed, it will ride over the cam surface 36 70 until the keeper receiving recess 34 is reached.

The construction described is one which has proved very practical in all respects. The lock mechanism applied to the latch is simple and economical to make and assemble yet is especially effective for the purposes for which it was designed. The invention is defined in the appended claims and is to be considered comprehensive of all forms of structure coming within their scope. 75 80

I claim:

1. In a latch construction, a housing, a pivotally mounted lever mounted on said housing and located partly within the same and movable at its outer end to an upper or 85 a lower position, common means for releasably holding the lever in either of said positions, a base plate covering the inner side of the housing, and a lock bolt movably mounted thereon and movable to a position to engage with the said lever when it is in its lower position to prevent its movement to its upper position.

2. A latch construction comprising, a housing, a lever pivotally mounted between its ends on and within said housing, a part of 95 said lever extending through one side of the housing outside thereof, said outer portion of the latch lever being movable to an upper or a lower position, a base plate closing the inner side of the housing, and a lock bolt 100 slidably mounted thereon and movable to a position to interpose in the path of movement of the inner end of the lever when the outer end of the lever is in lower position, to 105 hold the lever against pivotal movement.

3. In a latch structure, a housing, a latch lever pivotally mounted thereon within the housing between its ends and having an outer 110 end portion extending through a side of the housing outside thereof, manually operable means for moving said lever, a base plate closing the inner side of the housing having guides struck therefrom, and a lock bolt 115 slidably mounted on the housing between said guides having a part movable to extend into the path of movement of the inner end of the latch lever when the outer end thereof is in its lower position, and prevent movement of the lever to raise the outer portion thereof to upper position.

4. In a latch housing, a latch lever pivotally mounted thereon within the housing and extending at one end portion thereof outside the housing, means for manually turning the lever about its pivot, a base plate closing the inner side of the housing, guides integral with the base plate, a locking bolt slidably mounted between said guides and movable when the outer end portion of the lever is in 120 125

a lower position to a position in the path of movement of the inner end of the lever, and spring means connected with the base plate and bearing against the inner side of the locking bolt to hold it between the guides 5 therefor and frictionally retain it in any position to which it is moved.

5. A construction containing the elements in combination defined in claim 4, wherein the means for securing said spring means to 10 the base plate comprises a tongue struck from the base and extending through said lock bolt, said lock bolt having a longitudinal slot therein for the passage of the tongue, and the spring means comprising a leaf spring bearing 15 against the inner side of the bolt through which said tongue passes, the end of the tongue being headed to retain the leaf spring in position against the bolt.

6. In a latch construction of the type described, a housing; a pivotally mounted lever mounted upon said housing and located partly within the same and movable at its outer 20 end to an upper or a lower position, a base plate covering the inner side of the housing and a lock bolt slidably mounted upon the base plate and movable to a position to engage with the said lever when it is in one of its positions to lock the same against movement.

30 In testimony whereof I affix my signature.
ANDREW EKMAN.
